H. B. HILLS.

SHIP'S DAVIT.

APPLICATION FILED JUNE 25, 1919.

1,332,387.

Patented Mar. 2, 1920.

UNITED STATES PATENT OFFICE.

HARRY B. HILLS, OF TOMPKINSVILLE, NEW YORK, ASSIGNOR TO STEWARD DAVIT & EQUIPMENT CORPORATION, OF NEW YORK, N. Y., A CORPORATION OF NEW YORK.

SHIP'S DAVIT.

1,332,337.

Specification of Letters Patent.

Patented Mar. 2, 1920.

Application filed June 25, 1919. Serial No. 306,512.

To all whom it may concern:

Be it known that I, HARRY B. HILLS, a citizen of the United States, residing at Tompkinsville, county of Richmond, and 5 State of New York, have invented certain new and useful Improvements in Ships' Davits, of which the following is a specification.

My invention relates to a ship's davit, and 10 it has for its object the provision of means whereby it can be lowered or moved from its operating position onto the deck of the boat and without being dismantled or taken down, so as to leave the space occupied by it 15 free for other purposes.

I will describe a ship's davit embodying my invention and then point out the novel features thereof in claims.

In the accompanying drawings, Figure 1 20 is a top view of a frame comprised in a ship's davit, partly in cross-section and embodying my invention. Fig. 2 is a side elevation of the davit shown in Fig. 1. Fig. 3 is a view showing in dotted lines how the 25 davit frame moves on its hinge. Fig. 4 is a view similar to Fig. 1, but showing a modification embodying my invention.

Similar letters of reference designate corresponding parts in all of the figures.

30 I will premise that my invention is applicable to that type of ship's davit which embodies a frame or other support on which is suitably mounted a boom, by means of which a lifeboat is launched or decked.

35 In the drawings I have illustrated only the frame or support of a ship's davit, because my invention is associated with it. The form of frame illustrated is substantially that shown in U. S. Patent No. 1,245,752,

40 granted November 6, 1917 to T. H. Marten, and my invention is particularly applicable to that form of ship's davit.

Referring to the drawings, A designates a suitable frame comprising a base *a* and uprights *a*¹, *a*². The frame may be constructed in any desired way in order to obtain the necessary strength and rigidness for the work to be performed. Preferably the frame is cast of metal and in a unitary structure. The frame is suitably mounted on the deck of a ship in a suitable position so that the boom mounted thereon may be moved outboard and inboard in launching and decking a lifeboat. As here shown the frame 55 is mounted on sole pieces B, and the sole

pieces are suitably fastened to the deck by means of bolts *b* or other fastening devices.

Suitably secured to the base *a*, where the uprights *a*¹, *a*² are joined to it, as by rivets *c*, are plates *C*¹, *C*², *C*³, *C*⁴, arranged in pairs. 60 The plates *C*¹, *C*² are larger than the plates *C*³, *C*⁴ and a greater number of rivets *c* are used, because these plates are on the inboard side of the davit and are subjected to greater strain. So far as my invention is concerned 65 however, they perform the same function as the plates *C*¹, *C*². Each plate has a hinge connection D with the adjacent sole piece B, and with one or more recesses *c*², each of which receives a tumble bolt E, which are 70 hinged on the sole pieces B. The frame A is held in its upright or operating position on the sole pieces B by means of the tumble bolts E.

It will be observed that when it is desired 75 to lower the davit onto the deck it is only necessary to remove all of the tumble bolts E from the recesses *c*² and turn the frame on a pair of its hinges D (see Fig. 3). One pair of hinges D is used to lower the davit 80 in one direction while the other pair is used to lower the davit in the opposite or reverse direction. I have only shown in the drawings two pintles *d*, and these as being removable, so that they may be used in either 85 pair of hinges.

In Fig. 4 I have omitted the sole pieces B. In this form of my invention the tumble bolts E are suitably secured to the boat deck as are the parts *d*³ of the hinges D. 90

My invention is particularly useful when lifeboats are located near a hatchway which is used for loading and unloading goods. The davits at these points may be lowered out of the way of the freight boom without 95 being dismantled and quickly put back into position after the loading or unloading is completed.

Having thus described my invention, what I desire to claim as new is— 100

1. The combination of a ship's davit frame, a pair of plates secured thereto, a hinged connection between each of said plates and the deck of the boat, and removable means secured to the deck of the boat 105 engaging said plates for holding the frame against movement on its hinged connections.

2. The combination of a ship's davit frame, a pair of sole pieces secured to the deck of a boat, a pair of plates secured to 110

the frame, a hinge connection between each plate and adjacent sole piece, and removable means carried by each sole piece and engaging its adjacent plate to prevent movement of the frame on its hinged connections.

5 In witness whereof, I have signed my

name to this specification, in the presence of two subscribed witnesses.

HARRY B. HILLS.

Witnesses:
